(57) **CLAIM**

The ornamental design for the light assembly, as shown and described.

DESCRIPTION

FIG. 1 is a perspective view of a light assembly, with the center portion broken away to indicate indeterminate length; FIG. 2 is a left side elevation view thereof, which is a mirror image of the right side elevation view; FIG. 3 is a top plan view thereof; FIG. 4 is a bottom plan view thereof; FIG. 5 is a front elevation view thereof; and, FIG. 6 is a rear elevation view thereof. The broken lines represent portions of the structure that forms no part of the claimed design.
